UNITED STATES PATENT OFFICE.

ADOLPH THOMMEN, OF NEWARK, NEW JERSEY, ASSIGNOR OF ONE-HALF
TO ENOS RICHARDSON & CO., OF SAME PLACE.

DESIGN FOR A MATCH-BOX.

SPECIFICATION forming part of Design No. 20,200, dated October 14, 1890.

Application filed September 11, 1890. Serial No. 364,700. Term of patent 14 years.

To all whom it may concern:

Be it known that I, ADOLPH THOMMEN, a citizen of the United States, residing at Newark, in the county of Essex and State of New Jersey, have invented and produced a new and original Design for Match-Boxes, of which the following is a specification, reference being had to the accompanying drawings, forming a part thereof, in which—

10 Figure 1 is a front perspective view of the match-box shown in my design; and Fig. 2 is a perspective view of the match-box, taken from the rear.

Similar letters of reference indicate corresponding parts in both views.

The leading feature of my design consists in the shape and ornamentation of the match-box, which presents the appearance in miniature of a newspaper enveloped by a wrapper, 20 the wrapper being provided with an address and having the usual stamp and date marked thereon. The general contour of the match-box is similar to that of a flattened irregular oval roll.

25 The central portion A of the match-box resembles in its general contour an ordinary newspaper-wrapper, the sides of the wrapper-like central portion being defined by the lines a, having notch-like figures a' thereon, and 30 on the back of the central portion the lines a are connected by the cross-line a², which thus simulates the flap of a wrapper. The front of the central portion has an address thereon, which may be the address of the owner of the 35 box, and near the upper right-hand corner of the central portion are the figures b and c, the figure b being made to simulate a postage-

stamp, and the figure c being made to simulate an ordinary post-office date-mark. On the back of the central portion A, as shown in 40 Fig. 2, on the cross-line a², at intervals, are the figures d, which simulate seals of wax.

The ends B of the box, extending from each end of the central portion A, are somewhat similar in shape, the central portion appearing raised slightly from the ends. The periphery of the box ends presents an irregular and somewhat jagged appearance, as represented by the lines e. The concentrically-curved lines e' thereon simulate the folds of a newspaper, 50 and on the front and back sides of the box ends are the figures f, which simulate the ordinary print of a newspaper. The box ends have also produced thereon on one side the longitudinal lines g, arranged in series, as 55 shown, and some of said lines have diagonally-extending branch lines g' leading therefrom, the said lines g and g' simulating the leaves of a newspaper. The figure b on the front of the central portion A may be made 60 to represent any kind of postage-stamp, and the figure c may be made to represent the post-office date-mark of any desired city or town.

The address on the center piece or wrapper 65 is not essential, and it may be omitted without affecting the character of my design.

I claim—

The design for a match-box herein shown and described.

ADOLPH THOMMEN.
